MATERIAL HANDLING APPARATUS

George L. Arms and Francis E. McGovern, Columbus, Ohio, assignors to The Jeffrey Manufacturing Company, a corporation of Ohio

Application December 23, 1937, Serial No. 181,385

12 Claims. (Cl. 209—273)

This invention relates to a method of and apparatus for handling granular material such as coal, gravel, crushed stone and similar material.

An object of the invention is to provide an improved method of and apparatus for handling material of the above mentioned class, particularly to classify the material as to size ranges and to convey material which is mixed with water while maintaining at a minimum the over-all height of the necessary equipment.

Another object of the invention is to provide a method and system of handling material which is mixed with water by separating the water from the material of relatively large size and employing at least part of the separated water to wash the smaller particles of material down a chute or flume.

Other objects of the invention will appear hereinafter, the novel features and combinations being set forth in the appended claims.

In the accompanying drawings,

Fig. 1 is a side elevation of an installation incorporating the features of our invention;

Fig. 2 is a longitudinal sectional view of apparatus incorporating the features of our invention;

Fig. 3 is a transverse sectional elevational view taken on the line 3—3 of Fig. 2 looking in the direction of the arrows; and

Fig. 4 is a transverse sectional view taken on the line 4—4 of Fig. 1 looking in the direction of the arrows.

In the construction of a modern coal cleaning plant or tipple every effort is made to maintain the height of the building at a minimum, for the building height is a very important item in the total cost of such a plant. The present invention is designed with this basic principle in mind and it relates particularly to apparatus for treating the coal which is mixed with water after it issues from the coal cleaning unit such as the jig. The apparatus and method are also useful, however, in the treating of other material, such as gravel, crushed stone, etc.

Referring particularly to Fig. 1 of the drawings there is illustrated, an upper de-watering screen 10 which, in the complete installation, is positioned to receive coal mixed with water from the coal cleaning unit, such as the jig. The upper de-watering screen 10 is pivotally mounted upon hanger rods 11, 11 supported upon a superstructure 12 for shaking movement and is oscillated by a crank rod 13 driven by a crank shaft 14 to which is connected a drive pulley 15 driven by an electric motor 16. The bottom plate of the

upper de-watering screen is provided with relatively large perforations which, by way of example, may be one and one-quarter inch, thus permitting a range of material below this size to pass therethrough. Larger material received by the screen 10 will be discharged over its discharge end to an upper sizing screen 17 pivotally mounted upon superstructure 12 by hangers one of which is seen at 18. The upper sizing screening 17 will have a perforated bottom plate to discharge material of a predetermined size onto a lower sizing screen 19 also supported from the superstructure 12 by hangers one of which is seen at 20.

Positioned below the upper de-watering screen 10 to receive the size range of material which passes through it is a lower de-watering screen 21 which is pivotally mounted upon hangers 22, 22 carried by superstructure 12.

Oscillation of the lower de-watering screen 21 is effected by a crank rod 23 also connected to the crank shaft 14. The crank rods 13 and 23 are connected 180 degrees out of phase with respect to the crank shaft 14 thereby counterbalancing the forces on said crank shaft.

It is to be noted that the upper de-watering screen 10 and the lower de-watering screen 21 slope downwardly from their material receiving ends to their material discharge ends and this slope, particularly in combination with the oscillatory movement which they receive, will cause any material on them to flow downwardly to their discharge ends. It may be mentioned that instead of having the sloping screens 10 and 21 these screens may be made horizontal and given a conveying action by inclined supporting cantilevers in a manner well understood in the screen art.

Adjacent the lower or discharge end of the de-watering screen 21 we provide a chute 24 which conveys the material received by said screen 21 and incapable of passing through the perforations in the bottom thereof, and delivers it to a mixing conveyor 25. The chute 24 is preferably provided with one-quarter inch perforations along the area 26 which will allow the very fine degradation to pass from said chute 24 and into a hopper 27 from which it will be conveyed to a slack car or to equipment for further treating. As was previously pointed out, the upper de-watering screen has perforations in its bottom plate which may be of one and one-quarter inch size and thus the lower de-watering screen 21 will receive material of one and one-quarter inch by zero (1 1/4" x 0) size range.

The bottom of the lower de-watering screen 21 is in the form of a screen cloth 28 which extends substantially the entire length thereof and, as an example, may be of three-quarter inch mesh. 5 Said screen cloth is sectioned, however, by a plate 29 which is necessary to provide room for the crank shaft 14 which extends therebelow.

Positioned below the lower de-watering screen 21 is a flume or chute 30 which slopes in a direction opposite to that of the screen 21. It will be noted that the slope of the de-watering screen 21 is relatively gradual and is less than the angle of repose of the material, such as coal, which is being treated. However, since this screen is given 10 a reciprocatory motion the coal will pass readily thereover from the receiving end to the discharge end. The flume 30, however, is stationary as it is supported from the foundation or a main frame of the building 31 by spaced supports 32, 32. 15 20 In order to maintain the over-all height of the building at a minimum, thus to keep down the cost of the complete installation, the slope of the flume 30 is relatively gradual and is appreciably less than the angle of repose of the material being treated. It is, of course, evident that the water and fine material below three-quarter inch mesh which passes through the screen 21 will be received by the flume 30. Due to the slight incline thereof, as above set forth, there is a definite 25 30 tendency for the material to pile up on the bottom of said flume and not flow down it. This is particularly true in view of the fact that the mixture of coal and water which is received by the lower de-watering screen 21 is received to 35 a large extent adjacent the topmost portion thereof or receiving portion 33. Of course, material will be received by flume 30 through substantially the entire length of the screen 21 as it passes through the openings in the upper de-watering screen 19 but substantially all of the water which is mixed with the coal will flow from the upper de-watering screen 19 immediately upon the reaching of the perforations in the bottom thereof and, in turn, will likewise 40 45 flow through the receiving portion 33 of the lower de-watering screen 21 and into the lower end of flume 30. As a consequence, the material which passes through the intermediate and lower portions of the screen 21 are substantially 50 55 devoid of water and thus do not flow freely when received by the flume 30.

In the method and apparatus of our invention we intercept a portion of the water mixed with the coal and convey it to a position adjacent the 55 upper end of the flume 30 where its direction of travel is changed so that it is discharged onto the bottom plate of said flume 30 in a direction which it thereafter flows along said flume bottom. In this manner a free flow of the material 60 on the relatively gradually sloping flume 30 is assured without requiring the addition of any water over and above that which is in the unsized material as it is received from the jig, except possibly for a slight amount of water which 65 is used to wash off the coal, as hereinafter described in full detail.

In order to accomplish the above described results we provide a plurality of longitudinally extending pipes 34 between the screen 21 and the 70 flume 30 which slope downwardly with said screen 21 and are supported in said flume 30. Adjacent their lower ends the pipes 34 terminate in a nozzle 35 which is formed by a transversely extending plate 36 which extends between the side 75 plates 37, 37 of the flume 30 and is provided with

three apertures through which the three pipes 34 extend and to which said pipes 34 are welded.

Rigidly attached to the top of the plate 36 and to the side walls 37 of the flume 30, we provide a plate 38 which is curved at 39 to change the direction of travel of the water and to discharge it onto the bottom of the flume 30 in the direction the water will thereafter normally flow down said flume.

The nozzle 35 also includes a bottom plate 40 10 which is welded at one end to the transversely extending plate 36 and extends between the side plates 37, 37 and is welded thereto. The upper end of the plate 40 is spaced slightly from the curved plate 38 to form an elongated restricted 15 opening or orifice 41 which extends transversely of the entire width of the flume 30. The orifice 41 preferably has an area which is substantially equal to the combined areas of the three pipes 34 so that the water issuing from said orifice 41 will have substantially the same velocity as the water as it flows through said pipes 34. It is thus to be seen that the water which flows downwardly by gravity through the pipes 34 in three separate streams is formed into a sheet which extends substantially the full width of the flume 30 and is discharged onto the bottom of said flume at a position near the top thereof and in the direction which the water normally flows along said flume or, in other words, along the direction of incline 20 25 30 thereof.

It is also to be noted that the bottom-most portion of the plate 38 is spaced slightly above the bottom of the flume 30 to allow material to pass thereunder as hereinafter described. In addition, the curved portion 39 of said plate 38 is provided with a small transversely extending opening or a plurality of drill holes 42 extending transversely thereof to permit a small amount of the fluid which is discharged from the opening 40 to pass to the bottom of the flume 30 at a position above that where the main sheet of water is discharged onto said flume. This is provided because in practice it has been found that there is a tendency for a small amount of material to accumulate in the uppermost portion of the flume 30 and this small stream or spray of water is sufficient to wash this material down the flume with the main material received thereby. The positioning of the bottom-most portion 40 45 50 55 of the plate 38 above the bottom of the flume 30, of course, allows this material to flow with the water readily thereunder.

In order to insure the proper distribution of the water which flows from the curved plate 38 onto the bottom of the flume 30 where the material to be picked up by said water is concentrated on the bottom of said flume 30, we also preferably provide a plurality of spaced upstanding distribution plates 43 which are spaced to 60 form the bottom of said flume 30 into three separate troughs, thereby insuring a complete removal of all of the material which falls on the bottom of said flume 30.

It may additionally be pointed out that the lower de-watering screen 21 carries a transversely inclined guide plate 44 at its discharge end which slopes downwardly opposite the sloping of said screen 21 and directs any material which is received thereby onto the bottom of the flume 30 below the nozzle 35. This plate 44 will, of course, clear itself because it reciprocates with the screen 21.

A guide plate 45 is also provided near the upper or feed end of the screen 21 which plate 45 is 70 75

part of the stationary flume 30. This plate will, however, clear itself readily as it has a fairly steep slope and, in addition, there will be a fair amount of water with the coal which discharges 5 onto said plate 45.

It may also be noted that any coal which passes through the receiving portion 33 of the screen 21 is received by the flume 30 near the discharge portion thereof and is guided thereto by a stationary guide plate 46 which not only has a relatively steep slope but will also receive an appreciable amount of water.

In order to intercept a portion of the water which discharges largely through the screen 21 15 at the receiving portion 33, the upper ends of the pipes 34 are slit open, as clearly illustrated in Fig. 4 of the drawings, and provided with outwardly extending flanges 47 which provide effective receiving hoppers for the pipes 34. The 20 upper ends of the pipes 34 are preferably closed by plates 48 thus completing the structure of said water receiving hoppers. It is to be noted that the hoppers are laterally spaced apart, as clearly 25 illustrated in Fig. 4 of the drawings, as a consequence of which they do not intercept all of the water which passes through the receiving portion 33 of the screen 21, but do intercept a substantial amount of it, sufficient to insure the free flowing of the material along the flume 30.

It is additionally to be noted by reference to Fig. 1 of the drawings that we have provided sprinkler washing means comprising a spray pipe 49 having a plurality of transversely extending spray nozzles 50 which spray the coal 30 on the upper de-watering screen after it has been denuded of the larger portion of the water which flowed with it from the jig and also a plurality of transversely extending nozzles 51 which spray the coal on the lower de-watering screen 21 after 35 it has been robbed of most of the water with which it was mixed in the jig. This spray means is for the purpose of making the coal clean and bright, as the water with which it is mixed in the jig is often dirty.

In the operation of the apparatus with the consequent realization of the method comprising our invention, material such as cleaned coal is received from a jig by the upper de-watering screen 10 which screen is in vibration. The principal 40 portion of the water in the mixture will flow through the screen as soon as the perforations in the bottom thereof are reached and will flow immediately to the lower de-watering screen 21. The wet coal on the screen 10 will then travel 45 down said screen by which it will be separated according to size ranges with the larger particles de-watered by the vibration of screen 10 and discharging over the end thereof to be further treated by the sizing screens 17 and 19. The 50 smaller particles of coal, for example, minus one and one-quarter inch, will be shaken relatively free of water and discharged onto the lower de-watering screen 21. It may also be mentioned that after the discharge of the water which is 55 mixed with the coal by the screen 10 said coal will be washed by the spray means 50 to remove any adhering dirt.

The water which passes first through the 60 screen 10 and onto the screen 21 will, of course, also contain some coal and this water with the relatively fine particles of coal will immediately pass through the receiving portion 33 of the lower de-watering screen 21 and into the discharge end of the flume 30 except that which is 65

caught or intercepted for further use, as herein-after described.

The fairly de-watered material on the immediate and lower portions of the screen 21 will be further de-watered and classified according to 5 size with the smaller particles thereof passing through said screen and into the flume 30, the larger particles passing over the discharge end of the screen 21 and into the conveyor 25 by way of the chute 24. The screen 26 of the chute 24 10 will remove any degradation below one-quarter inch and discharge it into hopper 27 from which it will be taken for further treatment. It will be evident that the oscillatory motion of the screen 21 will not only cause a conveying action 15 on the material but will also aid in freeing it of adhering water particles.

It will thus be seen that the material received by the mixing conveyor 25 and by the upper and lower sizing screens 17 and 19, will be graded according to size, will have been washed free of dirt particles received in the jiggling or cleaning operation and will be delivered relatively free of water, though, of course, the said particles will 20 be damp.

The smaller size ranges of materials as determined by the size of the screen cloth 28 which, for example, may be minus three-quarter inch, will be received by the flume 30 and washed 25 downwardly from said flume by the water which is intercepted by the pipes 34 as it passes through the receiving portion 33 of the screen 28 and is discharged in a sheet over substantially the entire width of the bottom of the flume 30 adjacent the upper end thereof and in a direction 30 in which the water normally flows thereafter down said flume 30.

It may be mentioned that the discharging of this sheet of water is preferably in the direction it flows down said flume 30, as aforesaid, to insure its direct straight-line motion along said bottom of the flume 30 which prevents any whirlpools and thereby prevents any accumulation of material on the bottom of the flume 30. In other words, this insures a rapid straight-line 35 motion of the water along the bottom of the flume 30 which will insure the carrying away of the coal received thereby.

It should be understood that while the water with the clean coal from the jig may be relied 40 upon to supply the flume 30, the amount may be supplemented by the spray water from the nozzles 50 and 51. Valves for the nozzles 50 and 55 may be supplied so as to secure a regulation of the water flow along the flume 30. It is preferred to locate the nozzle 50 directly above the upper open or hopper ends 47, 48 of the pipes 34, so that the spray water may pass through the screens 10 and 21 in succession and thence into the hoppers. The spray water from the nozzles 60 51 passes through screen 26 (Fig. 2) directly to the bottom of the flume 30.

Obviously those skilled in the art may make various changes in the details and arrangement of parts without departing from the spirit and 65 scope of the invention as defined by the claims hereto appended, and we therefore wish not to be restricted to the precise construction herein disclosed.

Having thus described and shown an embodiment of our invention, what we desire to secure by Letters Patent of the United States is:

1. In material handling apparatus, the combination with a screen having a feed end and a discharge end, of a sloping flume positioned to 70

- catch directly material passing through the entire area of said screen, means for catching water which passes through said screen adjacent the feed end thereof and conveying it to a position adjacent the top of said flume, and means constructed and arranged to cause said water to discharge onto the flume in the direction of the slope thereof.
2. In material handling apparatus, the combination with a screen and a sloping flume positioned immediately below it to catch directly material which passes through said screen, of means for feeding granular material and water to said screen, means for intercepting at least part of the water in said material and conveying it separately from said material received by said flume from said screen to a position adjacent the top of said flume, and means for discharging said intercepted water onto the flume adjacent the top thereof in the general direction of the slope thereof.
3. In material handling apparatus, the combination with a screen, a sloping flume positioned immediately below it to catch directly falling material passing through the entire area of said screen, and means for catching water passing through said screen and conveying it to the top of said flume comprising a pipe positioned below said screen having an open top and water catching flanges, said open top and flanges being positioned adjacent the material receiving end of said screen.
4. In material handling apparatus, the combination with a screen having a feed end and a discharge end, of a sloping flume positioned immediately below said screen with the top adjacent the discharge end thereof, means for catching liquid which passes through said screen at its feed end and discharging it onto the top of said flume comprising a plurality of spaced sloping pipes positioned between said screen and flume and having their upper ends open and positioned to catch fluid passing through the feed end of said screen, said pipes having laterally extending fluid catching flanges along their open sides.
5. In material handling apparatus, the combination with a screen having a feed end and a discharge end, of a sloping flume positioned immediately below said screen with the top adjacent the discharge end thereof, means for catching liquid which passes through said screen at its feed end and discharging it onto the top of said flume comprising a plurality of spaced sloping pipes positioned between said screen and flume and having their upper ends open and positioned to catch fluid passing through the feed end of said screen.
6. In material handling apparatus, the combination with a sloping screen having a material receiving upper end and a material discharging lower end, of means for vibrating said screen, means for feeding a mixture of granular material and water to the upper end of said screen, a flume positioned immediately below said screen having a bottom sloping oppositely to the slope of said screen and positioned to catch directly material which passes through said screen, and means for catching liquid which passes through the upper end of said screen and conveying it to the upper end of said flume where it is discharged in a sheet onto said flume and in the direction of the slope thereof comprising a plurality of pipes having receiving hoppers positioned below the upper end of said screen to receive water passing therethrough and a discharge nozzle fed

by all of said pipes having a continuous restricted opening with a width substantially equal to the flume and having curved plate means to change the direction of flow of water through said pipes to discharge it to said flume as afore- 5 said.

7. In apparatus of the class described, the combination with a screen, of a sloping flume positioned immediately therebelow to receive material directly passing through said screen with its top end adjacent the discharge end of said screen, means for feeding a mixture of granular materials and water to said screen, and means for intercepting some of the water in said feed and directing it to the top of said flume, said means including a member constructed and arranged to change the direction of travel of said intercepted water and to discharge it onto said flume in a sheet and in the direction said water flows down said flume. 20

8. In apparatus of the class described, the combination with a screen, of a sloping flume immediately therebelow positioned to receive material directly passing through said screen with its top end adjacent the discharge end of said screen, 25 means for feeding a mixture of granular materials and water to said screen, and means for intercepting some of the water in said feed and directing it to the top of said flume, said means including a member constructed and arranged to change the direction of travel of said intercepted water and to discharge it onto said flume and in the direction said water flows down said flume. 30

9. Screening and conveying apparatus for granular material mixed with water comprising 35 the combination with a screen, of a sloping flume positioned immediately therebelow and having its top adjacent the discharge end of said screen, means for intercepting part of the fluid mixed with said material and washing the material 40 down said flume therewith comprising a discharge nozzle having a portion curved to change the direction of travel of the intercepted fluid and having a wide mouthed restricted orifice and so constructed and arranged that said fluid will 45 discharge in a sheet into said flume in the general direction it thereafter flows down said flume. 50

10. In combination with a sloping flume, of means for feeding water thereto by gravity comprising feed pipe means sloping in a direction other than that of the flume, and a nozzle constructed and arranged to discharge water from said feed pipe means to said flume adjacent the top thereof in a sheet and in the direction it flows down said flume, said nozzle comprising a 55 curved plate for changing the direction of flow of the water, and cooperating plate means to form a restricting orifice.

11. In combination with a sloping flume, of means for feeding water thereto by gravity comprising feed pipe means sloping in a direction other than that of the flume, and a nozzle constructed and arranged to discharge water from said feed pipe means to said flume adjacent the top thereof in a sheet and in the direction it flows down said flume, said nozzle comprising a 60 curved plate for changing the direction of flow of the water, and cooperating plate means to form a restricting orifice, said curved plate having its bottom positioned above the bottom of 65 said flume and having an opening therein to permit fluid to flow onto said flume bottom at a position above that where the sheet of water is discharged thereon and to flow down said flume 70 under said plate. 75

12. In combination with a sloping flume, of
means for feeding water thereto by gravity com-
prising feed pipe means sloping in a direction
other than that of the flume, a nozzle con-
structed and arranged to discharge water from
5 said feed pipe means to said flume adjacent the
top thereof in a sheet and in the direction it
flows down said flume, said nozzle comprising a
curved plate for changing the direction of flow

of the water, and cooperating plate means to
form a restricting orifice, said nozzle being posi-
tioned above the bottom of said flume, and
means for supplying additional water to said
flume at a position above said nozzle, which 5
water flows down said flume under said nozzle.

GEORGE L. ARMS.
FRANCIS E. MCGOVERN.
